UNITED STATES PATENT OFFICE

FRANKLIN HUNT, OF CHICAGO, ILLINOIS, ASSIGNOR TO THE LIQUID CARBONIC CORPORATION, OF CHICAGO, ILLINOIS, A CORPORATION OF DELAWARE

ACCELERATOR FOR REFRIGERATION UNITS OF SODA FOUNTAINS

Application filed March 21, 1929. Serial No. 348,738.

In soda fountains of the mechanically refrigerated type a refrigerating element, commonly known as a cooler or boiler is placed in a water-tight compartment together with two coils of pipe, one of which is connected to a supply of carbonated water and the other of which is connected to a supply of uncarbonated water, the arrangement being such that a liquid such as water or brine contained in a compartment submerges the boiler and the two coils.

The water tight compartment is arranged within a casing which is insulated from the external air except as to its upper end, and this end is covered by a removable cover which, in some instances, is perforated at several points for the reception of containers which form covers for the perforations and receptacles for material to be kept cool, said containers projecting into the upper end of the compartment, generally above the normal liquid level therein.

In such an arrangement the thermic circulation of the liquid is somewhat sluggish and there is a tendency towards accumulation of ice upon the boiler, which accumulation decreases the refrigerating effect of the boiler.

The object of my present invention is to provide simple but efficient means for mechanically stimulating the circulation of the liquid around the boiler and cooling coils in such manner as to decrease the tendency to ice accumulation and thereby maintain, to a greater degree, the cooling efficiency of the boiler relative to the coils, the construction and arrangement of the mechanical circulation stimulator being such as to prevent, as far as is conveniently commercially practicable, the delivery to the refrigerated compartment of heat which is unavoidably developed by the continuous operation of the stimulator, the arrangement being also such that it will not detract from the aesthetic value of the fountains, or interfere with convenient operation.

The accompanying drawings illustrate my invention.

Fig. 1 is a vertical section of that portion of the soda fountain to which reference has been made, wherein the upper open end of the

receptacle is closed by a cover which itself forms a support and container of a plurality of separate containers;

Fig. 2 is a perspective view of the construction shown in Fig. 1;

Fig. 3 is a perspective view of a cover, of the character shown in Fig. 1, with my improved circulation stimulator supported thereby;

Fig. 4 is a perspective view of another form of cover in which my improved stimulator is carried, said construction, as well as that shown in Fig. 3, being of such character as to be applicable to soda fountains already in use, wherein normal thermic circulation of the liquid within the receptacle has been depended upon, and

Fig. 5 is an elevation of the terminal block shown in Fig. 1.

In the drawings 10 indicates the main body of a soda fountain with heat insulated walls of common character, the top of said main body being covered by a metal cover 11 which, together with the heat-insulated top, is perforated at 12 above the receptacle 13 within which is mounted the boiler 14, the coil 15 for carbonated water, and the boiler 16 for uncarbonated water.

In the form shown in Figs. 1 and 2 the receptacle 13, at one side, is provided with a chimney-like lateral extension 17 which extends downwardly from the top of the receptacle to a point well below the normal liquid level which is to be maintained in the receptacle, and at its lower end is preferably inclined inwardly and downwardly as indicated at 18. Above the open upper end of the chimney 17 the heat-insulated top of the main body 10 is perforated at 20 to receive a cylindrical shell 21 of heat-insulating and electrical insulating material. The upper end of this shell 21 is provided with an outwardly projecting flange 22 adapted to rest upon the cover plate 11, which is suitably perforated for the reception of the shell, and at its lower end is provided with an inwardly projecting flange 23.

Mounted in the top of the main body, alongside shell 21 is a terminal block 25, of electrical insulating material provided with

a pair of upwardly presented terminal clips
26 and 27.

Sleeved within shell 20 is a small electric motor 30 the axial length of which is considerably less than the axial length of shell 20 and which, at its outer end, is provided with a metallic cap or cover 31 having an outwardly projected circumferential flange 32 adapted to rest upon flange 22 of shell 20.

- 10 The motor unit 30—31 is held in place by metal screws 33 passing through flanges 32 and 22 and top plate 11 into nuts 34 in contact with the under surface of cover 11 so that the body of the motor is grounded on 15 the top plate 11.

Motor 30 is provided with terminals 35 arranged to be received in, and vertically withdrawable from, clips 26 and 27 and is, conveniently, provided with a switch 36 by means 20 of which supply of current to the motor may be controlled. The rotor of motor 30 is provided with a shaft 37 which, at its lower end, carries a downwardly-acting propeller 38, the length of the shaft being such that the 25 propeller will be submerged in the liquid in compartment 13 and, in the form shown in Fig. 2, will support the propeller at about the level of the upper end of the incline 18.

In the form shown in Fig. 4 shell 21 is supported in a metal cover 40 adapted to close perforation 12, being so arranged that propeller 38 will lie within the liquid in the compartment 13 at such point that the propeller may freely rotate without contacting 30 with the boiler or either one of the water coils. The axial length of shell 21 is such as to be less than the distance between the cover and the normal liquid level in compartment 13.

- 40 In the form shown in Fig. 3 the cover 50 for the perforation 12 is perforated at a plurality of points 51, some of which are closed by receptacles 52 each provided with a cover 53, and one of which is closed by a cover 54, 45 by which the motor unit is carried, as clearly shown in Fig. 3.

In the forms shown in Figs. 3 and 4 an electrical connector 55, leading to the motor, is provided for the reception of a portable plug 56 of ordinary form.

In each of the forms shown the arrangement is such that a forced down-flow of liquid in compartment 13 may be set up along a line somewhat removed from the boiler tubes, thus producing a forced upward movement of the liquid adjacent the boiler tubes and a consequent forced circulation of the liquid around the water coils in such manner that the tendency of ice accumulation upon the boiler tubes is retarded, thereby maintaining a higher cooling efficiency of the boiler relative to the water coils. Because of the metallic connection between the motor body and the extended metal cover plate of the main body of the fountain, the heat un-

avoidably generated by a continuous operation of the motor will, to a great extent, be dissipated by radiation and, because of the relatively deep shell 21 and the inwardly projecting flange 23, and the heat insulating character of the shell 21, the heat generated by the motor will not be dissipated downwardly to an objectionable extent, into the refrigerated compartment 13. 70

The metal cap 31 may be kept bright, so that its heat-radiating value may be high, and it may be given a pleasing contour, without sharp projections, so that it will not interfere with the operations of the soda dispenser. 80

I claim as my invention:

1. In a soda fountain, the combination with the main heat-insulated body having a perforated metal cover plate and a perforated top, a liquid-container arranged in said body below said perforations and a boiler of a mechanical refrigerator and water coils in said container, of a propeller arranged in said container below the normal liquid level thereof, and a small electric motor having a vertical shaft carrying said propeller, the body of said motor being grounded upon the metal cover plate.

2. In a soda fountain, the combination with
the main heat-insulated body having a per- 95
forated top, a liquid-container arranged in
said body below said perforation, and a boil-
er of a mechanical refrigerator and water
coils in said container, of a shell of heat-in-
sulating material projected downwardly to
ward the normal liquid-level in the container,
a small electric motor vertically removably
mounted in said shell and having a vertical
shaft projected below said normal liquid- 100
level, and a propeller carried by the lower
end of said shaft. 105

3. In a soda fountain, the combination with the main heat insulated body having a perforated metal cover plate and a perforated top, a liquid container arranged in said body below said perforations, and a boiler of a mechanical refrigerator and water coils in said container, of a shell of heat-insulating material projected downwardly toward the normal liquid-level in the container, a small electric motor vertically removably mounted in said shell and having a vertical shaft projected below said normal liquid-level, the body of said motor being grounded on the metal cover plate, and a propeller carried by the lower end of said shaft. 110 115 120

4. As an article of manufacture, a cover for the opening of a soda fountain which affords access to the mechanically refrigerated liquid-containing compartment thereof, which cover carries a downwardly projecting shell, and a small electric motor mounted in said shell, said motor having a vertical shaft provided at its lower end with a propell- 130

ler, the length of said shaft being sufficient to submerge the propeller in the liquid in the compartment.

tension, and a propeller carried by said shaft below the normal liquid level in said container.

5. In a soda fountain, the combination with the main heat-insulated body having a perforated top, a liquid container arranged in the body below said perforation and having a chimney-like extension at one side, said extension being provided with an inclined bottom wall, and a boiler of a mechanical refrigerator and water coils in said container, of a small electric motor arranged in vertical alinement with the upper end of said chimney-like extension and having a vertical shaft extending downwardly into said extension, and a propeller carried by said shaft below the normal liquid-level in said container and positioned to direct a stream against said inclined wall.

In witness whereof, I have hereunto set my hand at Chicago, Illinois, this 7th day of March, A. D. one thousand nine hundred and twenty-nine.

FRANKLIN HUNT.

75

10 6. In a soda fountain, the combination with the main heat-insulated body having a perforated metal cover plate and a perforated top, a liquid container arranged in the body below said perforations and having a chimney like extension at one side, said extension being provided with an inclined bottom wall, and a boiler of a mechanical refrigerator and water coils in said container, of a small electric motor arranged in vertical alinement with the upper end of said chimney-like extension and having a vertical shaft extending downwardly into said extension, and a propeller carried by said shaft below the normal liquid-level in said container and positioned to direct a stream against said inclined wall.

80

15 7. In a soda fountain, the combination with the main heat-insulated body having a perforated top, a liquid container arranged in the body below said perforation and having a chimney-like extension at one side, said extension being provided with an inclined bottom wall, and a boiler of a mechanical refrigerator and water coils in said container, of a small electric motor arranged in vertical alinement with the upper end of said chimney-like extension, a heat insulating shell shielding the motor from said top, a vertical shaft driven by said motor and extending downwardly in said extension, and a propeller carried by said shaft below the normal liquid level in said container.

85

20 8. In a soda fountain, the combination with the main heat-insulated body having a perforated metal cover plate and a perforated top, a liquid container arranged in the body below said perforations and having a chimney like extension at one side, said extension being provided with an inclined bottom wall, and a boiler of a mechanical refrigerator and water coils in said container, of a small electric motor arranged in vertical alinement with the upper end of said chimney-like extension, a heat insulating shell shielding the motor from said top, a vertical shaft driven by said motor and extending downwardly in said ex-
